TELEPHONE SYSTEM

Eugen Jauch, Berlin-Siemensstadt, Germany, assignor to Siemens & Halske Aktiengesellschaft, Wernerwerk, Siemensstadt, near Berlin, Germany

Application November 13, 1937, Serial No. 174,328
In Germany December 17, 1936

6 Claims. (Cl. 179—17)

The invention relates to a circuit arrangement for remote control systems and more particularly for telephone systems with party lines and central control stations. In such systems the restoration of the switches at the branch stations on the termination of a call is brought about by transmitting resetting impulses from the central station.

Arrangements are known in which the switches at the branch stations of party lines are influenced on the termination of a call by restoring devices in the central station until a testing device has established the fact that all switches have been restored to normal. These arrangements have the disadvantage that for example in the case of a switch jamming resetting impulses are permanently transmitted from the central station over the line whereby the line is blocked. It is also known to provide a time switching device in the central station of a party line which switching device connects resetting current to the party line for a predetermined time. This arrangement has the disadvantage that with normal restoration of the stepping switches an unnecessarily large number of impulses are transmitted and the connecting line cannot be released except after the expiration of a given time.

The invention aims on the other hand at avoiding the permanent transmission of resetting impulses in the event of a switch jamming in the branch station and the consequent permanent seizure of a party line and on the other hand at avoiding the transmission of unnecessary impulses when all switches have been restored to normal.

This is achieved by the invention in that when the fact is established that a switch has not been restored to normal a time switching device is influenced by the testing device and independently of the restoration of all the switches to normal prevents further transmission of resetting impulses and releases the party line.

Conveniently signalling devices are operated in the exchange on the operation of the time switching device. During the progress of a fresh call the signals are disconnected but are again operated if the fault remains uncleared after the termination of the call.

The invention will be described in greater detail with reference to the drawing.

The invention is, however, not limited to the arrangements shown in the drawing. Only the details of the circuit which are necessary for the understanding of the invention are shown.

In the drawing a plurality of branch stations T_1 and T_2 are connected to the party line VL . The connection of the party line VL to the individual branch stations takes place over stepping switches Wr_1 and Wr_2 etc., disposed at each branch station. The stepping switches at each branch station are connected to the a -lead of the connecting line both in the normal position and in a particular position which corresponds to the number of the branch station in question.

The establishment of a call does not concern the invention. It will only be mentioned that on the removal of the receiver at a branch station for the purpose of establishing an outgoing call earth potential is applied to the a -lead whereby the starting relay X in the exchange or control station VSt becomes energized. Relay X applies alternating current to the b -lead in the exchange and thereby causes all the relays O in the branch stations to energize. The O relays connect the stepping magnets Wr of the stepping switches to the b -lead whereupon these switches and the discriminator switch Da are advanced synchronously until a stepping switch has reached the calling stations contact.

The switching operations take place in a corresponding manner in the case of incoming calls.

The invention is concerned only with the restoration of all the stepping switches to normal.

So long as a call is in progress the discriminator Da and the switches Wr at the branch stations are away from the normal position so that relay A is energized over wiper da_2 , and the a -lead of the connecting line VL and the wiper wr at a station engaged in a call. When the subscribers replace their receivers the energizing circuit for relay A passing over the a -lead is broken. Relay A releases in consequence and connects an interrupter U to the b -lead of the connecting line over its contact $15a$ and at the same time at contacts $17a$ completes the stepping circuit for the rotary magnet Da of the common discriminator. Relay V is energized through the release of relay A and breaks the c -lead of the connecting line to the exchange at contact $24v$ and disconnects the common starting relay X at its contact $25v$. The stepping magnets Wr_1 , Wr_2 , etc., at all the branch stations and in addition the rotary magnet Da of the common switch are now influenced by the impulse sender U , the stepping magnets over earth, battery, impulse sender U , contact $15a$, wiper da_3 of the contact switch, the b -lead of the connecting line VL , wiper wr_1 of the stepping switch at station T_1 , magnet Wr_1 and earth (and correspondingly for Wr_2 etc.)

and the rotary magnet Da over earth, battery, impulse sender U, wiper da4 of the discriminator switch, contact 17a, rotary magnet Da and earth.

The transmission of the re-setting impulses over the b-lead continues until the discriminator Da reaches its rest position when the stepping circuit is broken at wiper da3. At this moment switches at the branch station will also be in the rest position if they have been advanced in synchronism with the discriminator switch Da.

If it should now happen that one or more of the switches for example that at station T1 should not have been restored to normal on account of the fault the following circuit is set up for the testing relay K in the exchange: earth, battery, relay K, contact 9j, the zero position of wiper da1 in the common discriminator, the b-lead, wiper wr1 away from the zero position of the switch Wr1 at the branch station T1, the stepping magnet Wr1 and earth. Relay K energizes in this circuit. At the same time the switch Wr1, provided that it is not mechanically locked, is advanced one step. Through the closing of contact 11k, the relay G is energized over earth, contacts 11k, and 12j, relay G, battery and earth. Through the closing of contact 13g, relay J is energized over earth, contacts 11k and 13g, relay J, battery and earth. Relay J opens contact 9j and thereby breaks the stepping magnet Wr1 and at contact 9j locks relay K in a locking circuit. In addition relay G is deenergized through the opening of contact 12j so that relay J is released through the opening of contact 13g and again connects relay K to the b-lead at contact 9j. If after this step the switch Wr1 is still away from the normal position the stepping magnet Wr1 of the switch Wr1 against operates over the circuit: earth, battery, relay K, contact 9j, the zero position of the switch, wiper Da1, the b-lead, wiper wr1, magnet Wr1 and earth. If on the other hand the switch Wr1 has reached the rest position no further energizing of the stepping magnet Wr1 takes place since the stepping circuit is broken in the rest position of the switch.

The switching operations would proceed in a similar way if further switches were away from the normal position.

In order to avoid a permanent transmission of resetting impulses and thus a permanent seizure of the party line in the event of one of the switches sticking, relay K switches on a time switching device, for example the thermo-relay Th, at contact 20k when relay K energizes. Since relay K holds up during the transmission of resetting impulses in the stepping circuit over the b-lead, and, when relay J energizes, over the operated contact 9j, and earth, the thermo-relay Th is connected to battery until relay K is disconnected. Relay V is held energized over contact 23k and on the termination of the connection is connected in a circuit passing over wiper da5 but is disconnected again when the wiper da reaches the rest position. In the time between the breaking of this circuit and the connection by relay K the relay V holds up on account of its slow-to-release feature. Through the energizing of relay V the party line is guarded as regards both incoming and outgoing calls until relay K is disconnected.

If, for example, as a result of the switch Wr1 sticking relay K does not release then after a given time which normally suffices to bring the switches at the branch stations to the normal position the thermo-contact th of the thermo-relay Th becomes operative and connects relay S

to battery. Relay S energizes and connects an alarm device AL (for example a lamp) over contact 21s and holds up over resistance Wi, contact 22s, the zero position of wiper da1, lead b, wiper wr1, stepping magnet Wr1 and earth. Through the switching over of contact 22s relay K releases and at contact 23k disconnects relay V. Contact 24v completes the c-lead of the connecting line VL and contact 25v the starting lead, in preparation. The party line is thus free again for seizure both in the outgoing and incoming directions independently of the existence of a fault, for example at station T1. The other branch stations on the party line are thus no longer prejudiced by a fault at any one branch station. The system is moreover so arranged that a fault remains signalled over relay S until cleared. When a new call is initiated the signalling is temporarily removed during the new call and reoperated again when this call is released in that relays K, Th, and S again energize and effect signalling on account of the maintenance of the fault, the example at switch Wr1, as described until the fault is removed by the supervisory operator.

Although in the arrangement described the switches at the branch stations are influenced over one lead and earth the invention is not limited to this particular embodiment. The switches can, for example, be arranged in bridge across the two leads of the common connecting line in the known way in which case the setting of the switches takes place by impulses in one direction and the testing for establishing the calling party by current in the opposite direction.

What is claimed is:

1. In a telephone system, a party line having a plurality of stations, a device at each station operated during the extension of a call for connecting one of the stations to the line, means for resetting said devices to normal on termination of a call, testing means operated when any of said devices fail to return to normal, means operated responsive thereto for causing the return of such devices to normal, and other means controlled by said testing means for rendering said last means ineffective after a predetermined time.

2. In a telephone system as claimed in claim 1, wherein said means operated responsive to the operation of the testing means causes the testing means to control the return of such devices to normal.

3. In a telephone system, a party line having a plurality of stations, a selector at each station operated during the extension of a call for connecting one of the stations to the line, means for resetting said selectors to normal on termination of a call, a device including a test relay operated thereafter when a selector fails to return to normal for causing the return to normal of such a selector, a delay device energized responsive to the operation of said relay for rendering said first device ineffective after a predetermined time, and signalling means operated responsive to the operation of said delay device when a selector has not been restored to normal.

4. In an automatic circuit arrangement, a control station, a line extending therefrom, a plurality of branch stations associated with the line, a device at each station, means for operating the devices at said branch stations to connect one of the branch stations to the line, means operated to return all of said devices at the branch stations to normal under control of the device at said control station, testing means operated when any of the branch station devices fail to return to nor-

mal, means operated responsive to the operation of said testing means for causing said branch station device to be returned to normal, and other means operated by said testing means for controlling the last means.

5. In an automatic circuit arrangement, a plurality of branch stations, a line comprising two conductors associated therewith, a connecting device at each station, means for causing the transmission of a series of impulses over one of the conductors, said devices responding simultaneously to said impulses for connecting one of the stations to the line, means for causing the transmission of another series of impulses over said one
- 10 conductor for causing the return of said devices

to normal, a testing relay operated thereafter over said one conductor when any of said devices fail to return to normal, means operated responsive thereto for transmitting a different series of impulses over said one conductor to return such devices to normal, and means controlled by the operation of said testing relay for releasing said line by rendering said last means ineffective after a given time.

- 15 6. In an automatic circuit arrangement, as claimed in claim 5, control means at each station, said means effective over the other of said conductors for controlling said first and second means.
